(57) **CLAIM**

The ornamental design for a mobile phone, as shown and described.

DESCRIPTION

FIG. 1 is a front perspective view of a mobile phone;
 FIG. 2 is a front view of the mobile phone of FIG. 1;
 FIG. 3 is a rear view of the mobile phone of FIG. 1;
 FIG. 4 is a left-side view of the mobile phone of FIG. 1;
 FIG. 5 is a right-side view of the mobile phone of FIG. 1;
 FIG. 6 is a top plan view of the mobile phone of FIG. 1; and,
 FIG. 7 is a bottom plan view of the mobile phone of FIG. 1.
 The broken lines showing of FIGS. 1-7 are for the purpose of
 illustrating the present invention and forms no part of the
 claimed design.
